(57) CLAIM

The ornamental design for a convertible athletic belt assembly, as shown and described.

DESCRIPTION

FIG. 1 is a front perspective view illustrating my design for a convertible athletic belt assembly in a closed position; FIG. 2 is a rear perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof;

FIG. 8 is a rear view thereof;

FIG. 9 is a front perspective view illustrating my design for a convertible athletic belt assembly in an open position;

FIG. 10 is a rear perspective view thereof;

FIG. 11 is a top view thereof;

FIG. 12 is a bottom view thereof;

FIG. 13 is a right side view thereof;

FIG. 14 is a left side view thereof;

FIG. 15 is a front view thereof; and,

FIG. 16 is a rear view thereof.

The broken, dashed-line disclosures in the figures are for illustrative purposes only and form no part of the claimed design.
